UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

TEMPORARY SPRINKLER CLOSURE.

Application filed July 19, 1921. Serial No. 485,839.

To all whom it may concern:

Be it known that I, ARTHUR C. ROWLEY, a citizen of the United States, residing in Philadelphia, Pennsylvania, have invented 5
Temporary Sprinkler Closures, of which the following is a specification.

This invention relates to improvements in 10 sprinkler heads for use in automatic fire extinguishing systems and more particularly has to do with closures for such heads, one 15 object of the invention being to provide a novel form of closure for emergency or temporary use, which shall itself embody an element in the form of a temperature-responsive link, permitting or causing automatic opening of the closure when the temperature in the vicinity of the sprinkler head rises to a predetermined point.

It is further desired to provide a relatively simple, conveniently usable, temperature-responsive closure for a sprinkler head, which may be quickly applied thereto after this has opened and while the liquid is flowing from it; the construction including a 25 number of coacting parts capable of automatically separating to again permit opening of the closure in case of a subsequent dangerous rise of temperature in its vicinity.

These objects and other advantageous ends 30 I attain as hereinafter set forth, reference being had to the accompanying drawings, in which,

Fig. 1 is a side elevation, partly in section, illustrating a sprinkler head equipped with 35 my invention;

Fig. 2 is a front elevation of the parts shown in Fig. 1;

Fig. 3 is a perspective view of one of the 40 lever elements of my temporary closure;

Fig. 4 is a perspective view of the second of the lever elements of the closure;

Fig. 5 is a perspective view of a well known form of temperature-responsive link for connecting the lever elements shown in 45 Figs. 3 and 4; and

Fig. 6 is a perspective view of the locking pin.

In the above drawings, 1 represents the 50 tubular base of a well known form of automatic sprinkler head, such as is commonly used in automatic fire extinguishing systems, and this has formed integral with it a threaded nipple 2 for application to the water supply pipe of the system. Above

the base is a seat structure 3 designed primarily to cooperate with a valve (not shown) which normally closes the outlet of the sprinkler. Integral with the base 1 is a pair of outwardly curved arms 4 joined at their upper ends and having mounted in them a screw or stud 5 axially in line with the longitudinal center line of the nipple 2, base 1 and valve seat 3. A water spreader 6 is customarily mounted on the screw 5 above the yoke. 55 60 65

As is understood by those skilled in the art, automatic sprinkler heads of the type illustrated normally include a pair of coacting levers mounted between the valve on the seat 3 and the inner end of the screw 5 and held in positions in which the valve is maintained closed, by a fusible link which connects the ends of two of their arms. When, owing to a predetermined temperature rise in the vicinity of the sprinkler head, this fusible link melts or releases the two lever arms to which it is attached, the latter separate and, owing mainly to the pressure of fluid in the sprinkler system, the valve on the seat 3 is forcibly removed therefrom, permitting usually an escape of air under pressure and shortly thereafter, water or other fire extinguishing fluid. 70 75 80

For the purpose of stopping this flow of fluid after it has performed its fire extinguishing function, or for closing the sprinkler head to permit the system again being put in service, I provide the temporary closure shown, which consists of a valve 7 preferably of rubber or other relatively resilient and compressible material mounted on one end of a lever plate 8, which has an elongated extension constituting a handle 9. This lever plate includes a hooked portion 10, a fulcrum portion 11 and an abutment 95 in the form of a transverse pin 12, which projects from both of the faces of said plate. The latter is designed to lie in a plane substantially parallel with the plane including the longitudinal center line of the sprinkler head with which it is used and coacts with a second lever plate 13. This latter has a curved guideway 14 for the reception of the end of the screw or stud 5, a pair of hooks 15 designed to extend on opposite sides of the lever plate 8 and engage the pin 12 and a third hook 16 between which and the hook 10 of the lever plate 8 extends a tempera- 100 105

ture-responsive link 17. It also includes a bearing edge 18 designed to cooperate with the fulcrum portion 11 of the lever plate 8 and has arms 19 extended on opposite sides 5 of said bearing edge. These arms with the hooks 15 serve to maintain the lever plate 13 in the same plane as the lever plate 8.

In order to assemble the parts of my temporary closure, the plate lever 13 is mounted 10 on the lever 8, as shown, and the fusible link 17 is engaged with the two hooks 10 and 16. Thereafter the link 13 is moved on its bearing edge 18 to apply a predetermined tension to the fusible link 17, after which the 15 pin 12 is inserted in an opening in the plate 8 in front of the hooks 15, so as to retain said parts in their assembled positions under the predetermined stresses.

The parts of the device will now maintain 20 their given positions as a unitary structure and when it is desired to stop the fluid flow from or temporarily close a sprinkler head such as that shown, the device is grasped by the handle 9 and its valve 7 is placed in the 25 discharge opening of such head so that it engages the seat 3. With this latter as a fulcrum, the handle 9 is now moved upwardly so that the curved guideway 14 is brought into engagement with the inner end 30 of the screw 5, and this upward movement of the handle is continued until the upturned end 20 of the guideway comes against the top of the yoke 4, thus preventing further movement.

35 The parts are so proportioned and have such dimensions that when they are given the above positions illustrated in Fig. 1, the rubber valve 7 is compressed to a greater or less extent and seals the outlet opening of 40 the sprinkler head. Moreover the guideway 14 is so curved that while its lower portion is considerably inclined to the horizontal, its upper part, particularly adjacent its upturned end 20, is inclined at a relatively 45 slight angle to the horizontal or to a line at right angles to the longitudinal center line of the sprinkler head, so that after the parts have been brought to the positions illustrated, the friction between the end of the screw 5 and the guideway keeps them in place. At 50 the same time the two plates 8 and 13 with the link 17 are placed under stress so that if there is a subsequent rise of temperature above the point at which said fusible link 17 is designed to release, the two hooked portion 10 and 16 of said plates will separate, permitting the toggle formed by the two lever plates 8 and 13 to break by reason of the 55 pressure on the valve 7 so that the fire extinguishing fluid of the sprinkler system may again be delivered from the sprinkler head.

60 It is to be noted that in order to attain the above results, the pin 12 or the point of engagement of said pin with the hooks 15,

must be to one side of the straight line connecting the center line of the valve and of the screw 5.

With the temporary closure made as described, it is possible to quickly close a sprinkler head which has opened for any reason, so that the fire extinguishing system of which it forms a part may be at once put under pressure and made ready for immediate service. At the same time, since my closure is itself temperature-responsive, the 75 sprinkler is again ready for service in the event of an abnormal temperature rise, so that said closure may be continued in use indefinitely or it may be used until a new 80 sprinkler head can be put in place of the one which had previously opened.

I claim:

1. The combination in a sprinkler closure 85 of two cooperating toggle elements of which one is fulcrumed on the other; a temperature-responsive link connecting said elements; and a rigid connection between the elements independent of their fulcrum normally 90 maintaining the link under tension.

2. The combination of two members; a valve carried by one of said members; a guide and a hooked structure carried by the other member, said members, being fulcrumed one on the other; a pin on the second member engaging the hooked portion of the first member; with a temperature-responsive link normally connecting said members.

3. The combination of a handle lever; a 100 valve mounted thereon; a second lever fulcrumed on the first lever, one of said levers having a pair of hooks respectively on opposite sides and the other having a pin engaged by said hooks, with a temperature-responsive link normally connecting said levers and thereby maintaining them under stress.

4. The combination in a sprinkler closure 105 of a pair of levers adapted for operation between the valve and the yoke of a sprinkler head and fulcrumed one on the other; a temperature-responsive link normally maintaining said levers under stress; with a rigid member independent of the sprinkler head and of the fulcrum for holding said levers and link together as a unitary structure.

5. A sprinkler closure consisting of two 110 levers fulcrumed together at a plurality of points and having portions formed to respectively engage the valve and the yoke of a sprinkler head; and a temperature-responsive link normally holding the levers together.

6. The combination in a temporary sprinkler closure of a lever; a valve thereon; a second lever fulcrumed on the first lever and having a hook; a pin in the first lever detachably engaged by the hook of the second lever; and a fusible link separably connecting the first and second levers in position to maintain the hook and pin under stress.

7. The combination in a temporary sprinkler closure of two lever plates having substantially flat portions lying in the same plane and fulcrumed one upon the other; 5 hooks projecting from one lever plate on opposite sides of the other; a pin passing through the latter lever plate and engaged by said hooks; a relatively fusible link separably connecting the lever plates and maintaining said hooks and pin under stress; with 10 a valve carried by one lever plate, the other lever plate being formed to cooperate with the yoke of a sprinkler head.

ARTHUR C. ROWLEY.
